UNITED STATES PATENT OFFICE

2,520,342

TOOL

Iver C. Ross, Springfield, Mass.

Application March 8, 1950, Serial No. 148,377

3 Claims. (Cl. 77—58)

2

My invention relates to new and useful improvements in tools and is directed more particularly to the provision of a tool adapted for boring and similar operations.

It is the principal object of my invention to provide a novel and improved construction of the type in which a tool has a tool carrier which is movable transversely relative to the axis of rotation of the device and there is the further provision of a means whereby the carrier may be moved manually or automatically all as may be desired, which improvements will eliminate the now present objectionable inconveniences in prior art tools.

With the above primary object in view, it is another object of my invention to provide a construction of the above described character which is relatively simple and compact in accordance with the demands and desires of manufacturers and purchasers alike and which is not only practical in its value but also reliable in its operation and thoroughly efficient in its use.

It is a still further object to provide a device which is constructed of relatively simple parts which are adapted to be readily assembled and which when once assembled are positively and securely retained in operative relationship and which cannot be readily separated from each other, either accidentally or otherwise.

Other prime objects of my invention include: first, the provision of a simplified construction and arrangement of components of a tool so as to provide an end product which is strong, durable and compact in its structure and is distinctive in its appearance; second, the securingment of a higher degree of accuracy in the manner of work performed therewith than has heretofore been possible with prior devices known in the art; third, the attainment of a higher degree of speed of construction and assembly of the device due to its simplification in design and its unique composition of parts; fourth, the attainment of a flexibility of a capability of adjustment by which a large variety of work can be produced by means of the same device; fifth, the achievement of a greater ease in adjustment and repairs; sixth, the provision of an improved tool which may be made more economically and with fewer operations in the manufacture of its parts, as well as in the assembly of the same, than prior devices known in the art, and seventh, the provision of a construction which may be readily installed with respect to the various purposes for which it is intended.

All of the above objects I accomplish by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Fig. 1 is a small scale side elevational view of

Fig. 1 is a small scale side elevational view of a tool embodying the novel features of my invention:

Fig. 2 is a plan view of the tool shown in Fig. 1 with the shank thereof removed; Fig. 3 is a view similar to Fig. 2 with the upper

Fig. 3 is a view similar to Fig. 2 with the upper rings removed from the tool;

Fig. 4 is a longitudinal sectional elevational view of the tool shown in Fig. 1; and Fig. 5 is an inverted plan view of the eccentric.

Fig. 6 is a front elevational view of the pawl.

30 Fig. 1 is a front elevational view of the pin carrier and ratchet ring of the device of my invention:

Fig. 7 is a plan view of the pawl carrier shown in Fig. 6;

Fig. 8 is a partial sectional plan view on the line 8-8 of Fig. 1 showing the means for ac-

Fig. 9 is a small scale elevational view of the

tool carrier slide.

40 to and forming a part of this specification, I have shown but one embodiment of my invention which is deemed preferable, but it is to be understood that changes and modifications may be made within the scope of the appended claims
45 without departing from the spirit of the invention.

50 Referring now to the drawing more in detail, and referring more particularly to the preferred form of my invention selected for illustrative purposes, I have shown a tool which includes a cylindrical body 2 which is hollowed out or otherwise provided with a cavity at 4 such as is best shown in Fig. 4.

53 A shank or stem 6 is adapted to be received in the bore of a spindle, chuck or the like for

rotation of the tool. A flange 8 of the stem 6 is secured to the upper side of the body 2 by any suitable means.

Openings 10 represent screw holes for receiving screws which secure the flange 8 to the body 2.

The upper portion of the body 2 is reduced in diameter so as to provide a circular hub 12 above a ledge or shelf 14 and a recess 14' for a gear is provided in the upper side of the hub 12 as may be observed by reference to Fig. 3.

A lower ring 16 is disposed around and rotatable relative to the body 2 and a lock ring 18 is in threaded engagement therewith, as shown in Fig. 4.

A ring gear 20 having internal teeth, as shown in Fig. 4, is rotatable around the hub 12 and is provided with a peripheral flange 22 which is disposed on the upper side of the ring 16 (see Fig. 4).

The rings 16 and 18 are threadedly engaged, as described, so that the lock ring 18 may be screwed downwardly onto the ring 16. The ring 18 has a flange 18' for clamping or binding on the flange of the gear 20 between the respective rings so as to prevent rotation of the gear relative to the rings. With the lock ring being screwed upwardly, the gear 20 is released for rotation as will be appreciated. With the flange 22 of the ring gear 20 clamped to the ring 16 by ring 18 the ring gear may be rotated by rotating ring 16.

A gear 24 disposed in the recess 14' is in mesh with the teeth of the gear 20 and it has a shaft 26 journaled in the body 2 which carries a bevel gear 24" disposed in the cavity 4 of the body 2.

A bevel gear 28, a worm 30 and a ratchet 32 are integral and are disposed in the cavity 4. They are rotatable on screws 34 which are in engagement with the body at opposite ends of the cavity 4, all as is shown in Fig. 4.

A tool carrier 36, an end view of which is shown in Fig. 9, is slideable back and forth in a groove of well known form which is provided in the lower side of the body.

A hub 40 of the slide is provided with a socket 40' for a tool and there may be a tapped hole 38 for a set-screw to secure a tool in the said socket 40'.

The upper side of the slide is provided with teeth or threads with which the worm 30 is in engagement, as shown.

As the gear 24 is rotated, in one direction or the other in its recess 24' and relative to the body, the slide 36 is moved through gears 24', 28 and 30 in one direction or the other to position the cutting edge of a tool carried by said member 36, relative to the axis of rotation of the body and shank. That is, the tool of slide 36 may be positioned relative to the axis of rotation of the device as may be desired.

The rotation of the gear 24 is accomplished by clamping or locking the gear 22 between the rings 16 and 18 and rotating the ring 16 relative to the body 2.

The skirt 16' of the ring 16 may carry graduations which are registrable with a zero index on the body 2 so as to indicate the relationship of the tool of the slide 36 relative to the axis of rotation of the body 2. Suitable means not shown, may be provided for releasably locking the ring 16 to the body. Thus, when ring 16 is free to turn relative to the body and when the ring gear 20 is clamped thereto by ring 18 relative rotation of the said rings and body will bring

about movement of gear 24 and of the slide relative to the longitudinal axis of the body for moving the tool relative to said axis.

A pawl carrier 50 is reciprocable in the body transversely to the axis of rotation thereof and is slotted longitudinally, as shown in Fig. 7. Pawls 52 in said slot are pivoted at 54. A spring 56 presses the pawls downwardly (see Fig. 6).

A pawl ring 58 is provided around and in which the ratchet 32 is rotatable. A ring actuator 60 is rotatable in the body 2 and has a pin 62 disposed in a slot 64 of the ring 58. By turning the member 60 in one direction or the other, the ring 58 is turned on the ratchet 32 in one direction or the other.

The ring 58 is open or slotted at 66 on the upper side thereof as shown in Fig. 6 and according to the position of the opening 66 one or the other of the pawls 52 engages the ratchet 32 and urges it in one direction as the member 50 is reciprocated.

The actuator is held against longitudinal displacement by a spring pressed detent 64 engaging an annular groove thereof all as is shown in Fig. 8.

In the position of the parts shown in Fig. 6, as the member 50 moves to the left, the right hand pawl engages and moves the ratchet counterclockwise and the pawl at the left is held by the ring from engagement with the ratchet. If the ring 58 is turned counterclockwise by the member 60, the pawl at the left engages and urges the ratchet clockwise as the member 50 moves to the right. The position of the ring 58 controls the action of the pawls.

The ring 16 has a central depending eccentric portion 70 (see Fig. 5). A ring 74 therearound is provided with a pin 72 depending therefrom which is disposed in a hole 74 of the pawl carrier 50.

With the shank secured in a rotating member and the rings 16 and 18 in unlocking relation so that the ring gear 20 is free to turn on the hub 12 of the body, the ring 16 may be grasped and held against rotation. The ring 74 then rotates with the body so that the eccentric portion of the ring 16 moves said ring 74 back and forth transversely of the axis of rotation of the body which brings about a back and forth movement of the pin 72 relative to the axis of rotation of the body so that pawl carrier 50 is reciprocated back and forth in the body. In this way one of the pawls of the carrier 50 engages the ratchet, in each movement of the carrier in one direction so that the slide is moved outwardly in a step-by-step manner. Thus while the body is in rotation by holding the ring 16, the slide 36 is moved in one direction or the other in a step-by-step manner by the reciprocation of the member 50.

Thus it will be seen that a cutting tool may be positioned relative to the axis of rotation of the body all as may be desired for various machining operations, or the tool may be moved in a step-by-step manner relative to said axis of rotation for the desired machining operations.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications

and variations as fall within the meaning and purview and range of equivalency of the appended claims are therefore intended to be embraced therein.

What it is desired to claim and secure by Letters Patent of the United States is:

1. A tool of the class described comprising in combination, a body having a shank for engagement by a rotating member for rotating said body, said body provided with a recess and a cavity, a tool carrier reciprocable in said body below said cavity, gearing rotatable in said cavity operably engaging said slide for reciprocating the same, a driven gear in said recess and operative connections between said gear and said gearing, a ring gear in engagement with said driven gear and rotatable on said body, a lower ring rotatable on said body, and a lock ring threadedly engaging said lower ring for releasably locking said ring gear thereto, whereby said carrier may be reciprocated as the ring gear is locked to the lower ring and rotating said ring relative to said body, a ratchet integral with said gearing, pawl mechanism for actuating said ratchet and gearing reciprocable in said body, and actuating means for said pawl mechanism operable as said body is being rotated and lower ring is held for relative rotation of said body and lower ring and said ring gear is released by said lock ring whereby said carrier is reciprocated in said body in step-by-step manner, said pawl mechanism including a member reciprocable in said body having separate ratchet engaging pawls swingable therein and a central member oscillatable relative to said ratchet engageable with said pawls to hold one or the other of said pawls out of engagement with said ratchet.

2. A tool of the class described comprising in combination, a body having a shank for engagement by a rotating member for rotating said body, said body provided with a recess and a cavity, a tool carrier reciprocable in said body below said cavity, gearing rotatable in said cavity operably engaging said slide for reciprocating the same, a driven gear in said recess and operative connections between said gear and said gearing, a ring gear in engagement with said driven gear and rotatable on said body, a lower ring rotatable on said body, and a lock ring threadedly engaging said lower ring for releasably locking said ring gear thereto whereby said carrier may be reciprocated as the ring gear is locked to the lower ring and rotating said ring relative to said body, a ratchet integral with said gearing, pawl mechanism for actuating said ratchet and gearing reciprocable in said body, and actuating means for said pawl mechanism operable as said

body is being rotated and lower ring is held for relative rotation of said body and lower ring and said ring gear is released by said lock ring whereby said carrier is reciprocated in said body in step-by-step manner, said pawl mechanism including an elongated member having opposed pawls swingable therein for engaging said ratchet and a control ring oscillatable around said ratchet adapted to permit one only of said pawls to engage said ratchet, and a member in said body for oscillating said ring.

3. A tool of the class described comprising in combination, a body having a shank for engagement by a rotating member for rotating said body, said body provided with a recess and a cavity, a tool carrier reciprocable in said body below said cavity, gearing rotatable in said cavity operably engaging said slide for reciprocating the same, a driven gear in said recess and operative connections between said gear and said gearing, a ring gear in engagement with said driven gear and rotatable on said body, a lower ring rotatable on said body, and a lock ring threadedly engaging said lower ring for releasably locking said ring gear thereto whereby said carrier may be reciprocated as the ring gear is locked to the lower ring and rotating said ring relative to said body, a ratchet integral with said gearing, pawl mechanism for actuating said ratchet and gearing reciprocable in said body, and actuating means for said pawl mechanism operable as said body is being rotated and lower ring is held for relative rotation of said body and lower ring and said ring gear is released by said lock ring whereby said carrier is reciprocated in said body in step-by-step manner, said pawl mechanism including an elongated member having opposed pawls swingable therein for engaging said ratchet and a control ring oscillatable around said ratchet adapted to permit one only of said pawls to engage said ratchet, and a member in said body for oscillating said ring, said actuating means including an eccentric portion provided on said lower ring and a ring relatively rotatable thereon with operative connections between said last-named ring and elongated member.
